UNITED STATES PATENT OFFICE

1,960,490

DUPLICATOR FEEDER

Hubert Jagger, Chicago, Ill., assignor to Ditto,
Incorporated, Chicago, Ill., a corporation of
West Virginia

Application December 16, 1931, Serial No. 581,297

8 Claims. (Cl. 101—133)

The invention relates to duplicating machines and particularly to an improved construction of feeding mechanism for feeding-card stock and the like to hectograph machines.

5 One of the objects of the invention is to provide a drop type of feeder in association with a paper tray, the parts being carried by the reciprocating carriage and operating to relieve the operator from the physical strain heretofore involved in feeding the blank sheets to the impression rollers.

10 Another object is to provide feeding mechanism of such a nature that a sheet deposited on the paper tray when the carriage is at the end of its rearward stroke will be held on the tray until it is released automatically and allowed to drop by gravity toward the feeding rollers when the carriage reaches its forward or initial position.

15 A further object is to provide feeding mechanism especially suited for feeding card stock which can be adjusted to properly and quickly release a card for feeding to the rollers and which can also be rendered inoperative when desired.

20 A further object is to provide mechanism for the purposes described which will be simple in construction, fulfill all requirements of service and manufacture, and whereby the quantity of work produced can be materially speeded up while eliminating excessive strain on the operator.

25 With these and various other objects in view, the invention may consist of certain novel features of construction and operation as will be more fully described and particularly pointed out in the specification, drawing and claims appended hereto.

30 In the drawing which illustrates an embodiment of the device and wherein like reference characters are used to designate like parts—

35 Figure 1 is an elevational view of a portion of a hectograph machine having associated therewith feeding mechanism constructed in accordance with the present invention;

40 Figure 2 is a fragmentary detail view taken substantially through the center of the paper tray and carriage and showing the construction of the feeding mechanism;

45 Figure 3 is a bottom plan view taken along the line 3—3 of Figure 1, and

Figure 4 is a sectional view taken along line 4—4 of Figure 1.

50 The invention is primarily adapted for association with hectograph machines wherein a carriage carrying an impression roller is adapted for reciprocation over a duplicating surface, and accordingly, Figure 1 discloses the above form of duplicator constructed of side frames 10 held in

spaced relation by tie rods 11 and suitably supporting a flat platen or printing bed 12, the bed having mounted thereon a gelatin band 13, which is wound at each end of the bed upon spindles 14. When it is necessary to present a clean surface of 60 gelatin for duplicating purposes the spindles are rotated to cause the band to travel over the printing bed being wound upon one spindle and un wound from the other.

55 Each of the side frames 10 presents a track 65 upon which is adapted to slide a carriage designated in its entirety 15. The carriage is provided with depending members 16 for supporting the same upon the tracks and includes spaced frame members 17 connected by end frames 18, 70 one end frame being provided with the adjustable stop 19 for engaging shoulder 20 on the side frame 10 to limit the travel of the carriage forwardly, that is, toward the operator. Suitably journaled within the carriage is a handle arm 75

casting designated in its entirety by 21, having journaled therein the impression roller 22 and secured thereto the handle 23 which is actuated by the operator to rock the casting to locate the impression roller in operative or inoperative positions. In the former position the roller is in engagement with the gelatin band 13, Figure 2, for the purpose of impressing a blank sheet or a master sheet upon the gelatin surface, while in 80 its inoperative position the roller is raised off of impression and is in spaced relation with the pressure roller 24 journaled in arms 25, pivotally secured at 26 to the side frames 18. It is thus seen that when the rollers are in inoperative position they are adapted to receive a sheet of paper 85 or a card, as the case may be, the same being directed between the rollers and into engagement with the margin stop 27, which functions to properly locate the marginal edge of the sheet with respect to the duplicating surface. The above 90 constructional features and mode of operation are well understood by those skilled in the duplicating art and as the same constitutes no part of the present invention further description is considered unnecessary.

100 Suitably secured by screws 28 to the frame member 17 of the carriage is a paper tray 30 provided with marginal flanges 31 and a depending upper flange 32. The tray is adapted to receive a margin guide 33 having a marginal flange 34, 105 which can be adjustably positioned transversely of the tray in order to accommodate various widths of paper, and accordingly is provided with a depending flange 35 engaging flange 32 of the tray. A spring clip serves to resiliently main- 110

tain the respective flanges in engagement and the guide in operative position, permitting, however, ready removal of the guide should the same not be required.

5 For supporting the feeding mechanism from the tray depending lugs 37 and 38 are secured in spaced relation to the tray by screws 39 and are located immediately above the carriage frame member 17. Journalled in the lugs is a transverse shaft 40, preferably of square cross section throughout that portion of its length confined between the lugs, but having rounded extremities 41 forming bearings by means of which the shaft is rotatable with respect to the tray. The 10 shaft forms a support for feeding arms 42 secured by screws 43 in spaced relation with the shaft and having integrally formed therewith an upwardly flanged extremity 44, the same connecting the arms and extending between the 15 flange member 17 and the pressure roller 24 and terminating adjacent the base of tray 30. As the shaft 40 is rotatable in the depending lugs resilient means must be provided for locating the arms in operative position, wherein the flange 44 projects above the base of the tray to retain thereon a sheet of paper or card, as the case may be. For this purpose a coil spring 45 is located on one 20 rounded extremity of shaft 40 and has one end bent over the lug 37 while the other end is engaged in notch 46 provided in the end of the shaft. The spring resiliently urges the shaft in a counter-clockwise direction, Figure 2, and in order to properly locate the arms in operative position adjustable screws 47 are threaded to the arms 25 42 and so positioned as to engage the underside of the frame member 17. The screws thus limit the upward movement of the arms and so position the marginal flange 44 in its proper relation with respect to the paper tray. Adjustment is 30 readily accomplished by merely rotating the screws, which can then be locked by means of the nuts 48.

The above construction provides a drop feeder which will function to retain the sheet to be duplicated on the tray until the feeding rollers are spaced for the purpose of having inserted between them the sheet to be duplicated. For this it is only necessary that the flange 44 be depressed which will release the sheet and the inclination 45 of the tray 30 is such that the sheet or card supported thereon will be caused by gravity to drop and to be thus directed between the rollers. Assuming that the carriage is in its extreme forward position, the travel of the sheet will continue 50 until it engages the margin stop 27 when the parts are in position for initiating a printing operation. The present invention renders the above operation automatic since the feeding mechanism is provided with a depending arm 50, non-rotatably secured to one end of shaft 40 and extending to a point below the printing bed 12 where the arm 55 will engage a fixed stop 51 located on the side frame 10 of the machine. Engagement of the arm with the stop will take place as the carriage reaches the limit of its travel in a forward direction, that is, immediately before the stop 19 will contact shoulder 20 to position the carriage forwardly of the machine.

In order to lock the feeding mechanism in 70 inoperative position the locking member 52 is slidably mounted on end 41 of the shaft adjacent lug 38, but is non-rotatably secured on the shaft by means of the diametrical slot 53 formed therein for engaging the pin 54 secured to the shaft, Figure 4. Extending from the locking member to-

ward the lug 38 is a stud 55 adapted to engage in notch 56 formed in the lug. The location of the notch is such that the member 52 must be rotated in a direction to render the arms inoperative, whereupon the member can be slid toward the right, Figure 4, to locate the pin in the notch. With the parts in this position the shaft is held from rotation in a counter-clockwise direction and as the spring 45 urges the shaft in the same direction the parts are held in inoperative position with the flange 44 being located below the paper tray 30.

The above provides a drop feeder which is simple in construction and which is designed to operate automatically by the travel of the carriage to release the sheet at the proper time for feeding to the rollers. The stock is dropped on the tray when the carriage is in a convenient position and thus relieves the operator from unnecessary strain in reaching for a sheet as standard practice requires. Also, it is unnecessary for the operator to maintain his grasp on the sheet, thus leaving his hands free for removing a discharged sheet and for placing the same on the tray for receiving them, the mechanism automatically presenting to the feeding rollers the next sheet to be duplicated. The duplicating operations are thus speeded up and more copies can be turned out in less time with less fatigue and strain on the operator.

By the provision of a locking member the arms can be held in position below the surface of the tray allowing operation of the duplicator according to standard practice, the locking means being rendered operative or inoperative as desired 95 and being associated with the mechanism in a manner so as not to interfere with or minimize its operating efficiency.

It will be understood that I do not wish to be limited by the exact embodiment of the device 115 shown, which is merely by way of illustration and not limitation, as various and other forms of the device will of course be apparent to those skilled in the art without departing from the spirit of the invention or the scope of the claims.

I claim:

1. In a duplicating machine, in combination, a reciprocating carriage having feeding rollers journalled therein, a paper tray secured to the carriage at an angle to the horizontal and directly 125 above the rollers to discharge to the rollers sheets of paper deposited thereon, feeding arms rotatably mounted in associated position with the tray, said arms holding the sheet supported on the tray but being operative to release the sheet, and means 130 carried by the carriage for rendering the holding arms inoperative.

2. In a duplicating machine, in combination, a reciprocating carriage having feeding rollers journalled therein, a paper tray secured to the carriage angularly with respect thereto, feeding arms positioned below said tray and being rotatably supported thereon, said arms in one position holding a sheet on the tray and in another position being operative to release the sheet, and releasable means 140 carried by the carriage for retaining the arms in said last mentioned position.

3. In a duplicating machine, in combination, a reciprocating carriage having feeding rollers journalled therein, a paper tray secured to the carriage, 145 feeding arms rotatably supported on the tray and having a flanged end projecting above the plane of the tray, resilient means holding the arms in projecting position, operating means actuated by movement of the carriage to rotate the arms to 150

- locate the flanged end below the tray, and means carried by the carriage and operative to lock the arms in position below the tray when desired. 80
4. In a duplicating machine, in combination, a reciprocating carriage having feeding rollers, a paper tray secured to the carriage, feeding arms rotatably supported on the tray and having a flanged end projecting above the plane of the tray, resilient means holding the arms in projecting position to hold a sheet on the tray, operating means positioned for actuation by movement of the carriage to locate the flanged end below the tray for releasing the sheet, and means carried by the carriage for locking the arms in the last mentioned position. 85
5. In a duplicating machine, in combination, a reciprocating carriage having feeding rollers, a paper tray secured to the carriage, feeding arms having a flanged end projecting above the plane of the tray, a shaft rotatably supported from the tray and having the arms secured thereto, a locking member non-rotatably mounted on the shaft, and a lug projecting from the member, whereby said arms may be locked in position so that the end does not project above the tray. 90
6. In a duplicating machine, in combination, a reciprocating carriage having feeding rollers, a paper tray secured to the carriage, feeding arms resiliently urged in a direction to project a flanged end above the plane of the tray, a shaft rotatably supported from the tray and having the arms secured thereto, a locking member non- 95
- rotatably but slidably mounted on the shaft, and a lug projecting from the member, whereby the member in one position locates the lug in the path of the shaft supporting means to lock the arms in inoperative position. 100
7. In a duplicating machine, a platen, a carriage mounted for reciprocatory movement over said bed, feeding rollers journaled in said carriage, a paper tray secured to the carriage, a paper stop movably mounted on the carriage, resilient means for holding said paper stop in a position wherein it holds a sheet of paper on said tray above said feeding rollers, means for displacing said paper stop against the action of said resilient means to release the paper on the tray, and means for regulating the amount of movement necessary to displace the paper stop from operative position. 105
8. In a duplicating machine, a platen, a carriage mounted for reciprocatory movement over said platen, feeding rollers journaled in said carriage, a paper tray secured to the carriage at an angle to the horizontal, a paper stop pivotally mounted in said carriage to hold a sheet of paper on said tray above said feeding rollers, resilient means for holding said paper stop in its functionally operative position, means for displacing said paper stop from its functionally operative position against the action of said resilient means, and means carried by the carriage for securing said paper stop in a functionally inoperative position. 110
